(57) CLAIM

I claim the ornamental design for a combined display device and mounting bracket, as shown and described.

DESCRIPTION

FIG. 1 is an elevated perspective view of the present invention, shown in an assembled arrangement;

FIG. 2 is an exploded perspective view of the present invention showing the novelty display a distance above the display holder;

FIG. 3 is a front view of FIG. 2;

FIG. 4 is a rear view of FIG. 2;

FIG. 5 is a right side view of FIG. 2, the left side is a mirror image of the right side;

FIG. 6 is a top view of FIG. 2; and,

FIG. 7 is a bottom view thereof.

The broken lines in the drawings depict environmental subject matter only and form no part of the claimed design.
